(57) **CLAIM**

The ornamental design for a bubble gun, as shown and described.

DESCRIPTION

FIG. 1 is a front view of the bubble gun in accordance with the present invention.

FIG. 2 is a rear view thereof.

FIG. 3 is a left side view thereof.

FIG. 4 is a right side view thereof.

FIG. 5 is a top view thereof; and,

FIG. 6 is a bottom view thereof.

The broken lines in the drawings show portions of the bubble gun and form no part of the claimed design.

1 Claim, 6 Drawing Sheets
